(57) **CLAIM**

The ornamental design for a cell phone and tablet holder, as shown and described.

DESCRIPTION

FIG. 1 is a perspective view of the cell phone and tablet holder;

FIG. 2 is a front view of the cell phone and tablet holder;

FIG. 3 is a side view of the cell phone and tablet holder;

FIG. 4 is a side view of the cell phone and tablet holder;

FIG. 5 is a top view of the cell phone and tablet holder;

FIG. 6 is a bottom view of the cell phone and tablet holder;

FIG. 7 is a back view of the cell phone and tablet holder;

FIG. 8 is a front perspective view of the cell phone and tablet holder wherein the front cover is rolled back; and,

FIG. 9 is a back perspective view of the cell phone and tablet holder wherein the back support is in the functional orientation.

The broken lines represent environment that forms no part of the claim.
